CATHODE-RAY WAVE GENERATOR

Carmen L. Cuccia, Princeton, N. J., assignor to
Radio Corporation of America, a corporation
of Delaware

Application May 28, 1948, Serial No. 29,860

3 Claims. (Cl. 250—36)

1

This invention relates to multivibrators and wave generators, and more particularly to such devices for operation at very high frequencies.

It has been customary in such devices to employ tuned circuits or time-constant circuits to determine the operating frequency which, therefore, has an upper limit due to the reactive components in such circuits.

The main objects of this invention are to extend the operating limit to very high frequencies and to simplify the circuits of multivibrators, as such, and as frequency controls for wave generators. Broadly, these objects are accomplished by using interelectrode capacities for reactance in combination with resistance in external circuits, and electron beam deflection for switching.

Another object is to vary and control the frequency by simple adjustment of resistance.

A related object is to generate waves of desired shape at the multivibrator frequency or a multiple thereof.

A further object is to provide a variable-frequency wave generator that does not use tuned circuits.

Other objects and advantages of the invention will become apparent from the following description in connection with the accompanying drawing in which:

Fig. 1 illustrates a multivibrator according to the invention;

Fig. 2 illustrates a multivibrator-wave generator according to the invention; and

Figs. 3 to 7 show various anode arrangements that may be used in the generator of Fig. 2.

In the several figures like reference characters indicate corresponding parts.

Referring to Fig. 1 reference character 10 represents an evacuated envelope for an electron tube in which are disposed an electron emissive cathode 11 partly surrounded by a shield 12 to which it may be electrically connected and provided with a lead 13 extending through the wall of the envelope. Adjacent the open part of shield 12 are accelerating electrodes 15, 16 provided with leads 17 and 18 respectively. Still further from the cathode 11 are deflecting electrodes 20 and 21 provided with leads 22 and 23 respectively. Reference characters 25 and 26 indicate anodes disposed so that a beam of electrons from the cathode 11 may strike either of them. Leads 27 and 28 provide separate external connections for the anodes 25 and 26. A shield 29 of mica or other suitable material may be disposed between said anodes if desired.

External circuits interconnecting the elec-

2

trodes above described may comprise a source of potential such as batteries 30 and 31 connected in series, the negative terminal being connected to cathode lead 13. The positive terminal of battery 30 is connected to leads 17 and 18 for supplying a relatively positive potential to the electrodes 15 and 16. The positive terminal of battery 31 is connected to anodes 25 and 26 through separate circuits, one of which comprises a load 32 in series with an adjustable resistance 33 connected to lead 27 and thence to anode 25. The other anode circuit comprises load 35 connected through adjustable resistance 36 to lead 28 and thence to anode 26. An adjustable tap 37 on resistance 36 is connected to one end of a potentiometer 38, the other end of which is connected to cathode lead 13. The lead 23 makes adjustable contact with potentiometer 38 for adjusting the potential of electrode 21. Similarly, an adjustable tap 40 on resistance 33 is connected to one end of a potentiometer 41, the other end of which is connected to cathode lead 13, a contact on said potentiometer being connected to lead 22 for adjusting the potential of electrode 20.

The arrangement of Fig. 1 is a multivibrator which operates as follows. Cathode 11 may be heated in known manner and electrons emitted thereby are directed toward the anodes 25, 26 by the shield 12 which prevents electrons from being emitted except from its open portion. The positive potential applied to electrodes 15, 16 from the battery 30 accelerates the electrons and the electrostatic lines of force thereby set up in the region between said electrodes and shield 12 concentrate the electrons in a beam which, in a balanced condition, projects in the direction of the tube axis. The beam-forming members may be called an electrostatic lens. The beam normally would be split by the shield 29 and the electrons would be divided between the anodes 25 and 26. However, there is usually some unbalance which, for instance, causes most, or at least a preponderance, of the electrons to strike anode 25 and thereby set up an anode current from the batteries 30, 31 through load 32, resistance 33, lead 27, to anode 25, and thence to cathode 11. This anode current causes a potential drop in resistance 36 which reduces the potential of electrode 20 according to the position of tap 40. Inasmuch as the anode 26 is receiving very few or no electrons, there will be very little or no anode current in resistance 36 and the potential of the corresponding deflecting electrode 21 will be determined primarily or solely

by the position of lead 23 on potentiometer 38. The potentiometer is so adjusted that the positive potential of electrode 21 is sufficient to deflect the electron beam to the anode 26 without attracting the beam to itself. Hence, the reduction of the potential of deflecting electrode 20 as described above, permits the higher potential of electrode 21 to deflect the beam from anode 25 to anode 26. The resulting anode current through resistance 36 reduces the potential on electrode 21 and at the same time the potential on electrode 20 is restored to the value determined by the position of lead 22 on potentiometer 41. This relatively higher potential on electrode 20 causes deflection of the beam back to anode 25. The beam is thus deflected alternately between anodes 25 and 26 at a frequency which is determined by the circuit parameters, such as the interelectrode capacities and the adjustments of external resistances 33 and 36 and potentiometers 38 and 41. The oscillations thus set up by the multivibrator may be utilized in the load circuits 32 and 35.

Referring to Fig. 2 a similar multivibrator is provided with an envelope 10, cathode 11, shield 12, deflecting electrodes 20 and 21, anodes 25 and 26, and external circuits comprising a resistance for each anode and a potentiometer for each deflecting electrode, as described in connection with Fig. 1. In the Fig. 2 arrangement the electrodes 15 and 16 and battery 30 have been omitted so that deflecting electrodes 20 and 21 also function as beam concentrating accelerating electrodes.

A separate anode 45 is provided in the arrangement of Fig. 2 and it may be connected to an external circuit comprising a lead 46, a load 47, source of variable anode potential 48 and ammeter 49 which is connected to cathode lead 13. The output circuit just described utilizes oscillations generated by the sweep of the electron beam across the anode 45. This sweeping or switching action is obtained by the multivibrator action of anodes 25 and 26 and their associated electrodes and circuits as described in connection with Fig. 1. The frequency of the oscillations thus generated is determined by the frequency of the multivibrator and the wave shape is determined by the configuration and relative disposition of anodes 25, 26, and 45.

Fig. 3 illustrates an arrangement in which a separate or additional anode 50 is disposed further from the cathode than the anodes 25 and 26 and receives the beam of electrons through the space 51 between said anodes. This arrangement provides a sharp cutoff for the edges of the beam and is useful in generating square waves.

Fig. 4 shows another arrangement wherein an anode 52, having a relatively small cross-section perpendicular to the beam, is disposed closer to the cathode than the anodes 25 and 26 and preferably is in alignment with the space 51 therebetween. If the anode 52 is made very narrow, such as in the form of a fine wire or thin strip, the generator will produce an output wave consisting of sharp pulses, the width of which is determined primarily by the width of the electron beam.

Fig. 5 illustrates another modification in which a number of small cross-section anodes 54 are disposed between the cathode and the anodes 25 and 26. The anodes 54 preferably are spaced equal distances apart and connected to a common lead 55. The connections should be made at the extreme ends of said anodes so that lead

55 will not be struck by the electron beam and thereby act as an anode. In this arrangement a pulse is generated as the beam passes each of the anodes 54 and thus produces successive pulses having a frequency which is a multiple of the beam deflection frequency. Hence, with the anode arrangement of Fig. 5, the tube and circuit arrangement of Fig. 2 becomes a multivibrator-frequency multiplier.

Another anode arrangement is illustrated in Figs. 6 and 7, the former being an edge view and the latter being a perspective view. The anodes 57 and 58, which correspond in function to anodes 25 and 26, have disposed therebetween an additional anode 60 which may have such configuration that it will produce a desired wave shape when the electron beam sweeps across it. The anodes 57 and 58 are cut out as shown at 61 and 62 to accommodate the shape of anode 60. As the electron beam sweeps from left to right it will first strike entirely on anode 58 and then the beam will be divided between anodes 58 and 60 according to their relative configurations. In the region 63 between anodes 57 and 58, the anode 60 will receive substantially all of the beam electrons and thereafter anode 57 will receive a greater and greater proportion thereof according to the relative configurations of anodes 60 and 57. The process and wave shape are reversed when the beam sweeps from right to left.

The above arrangements provide both a multivibrator and a wave generator which latter may be also a frequency multiplier. Very high frequencies are obtainable with the arrangements disclosed due to the small reactance of the interelectrode capacities and the use of resistances in the external circuits. Obviously, the arrangements can be used for lower frequencies by providing inductance or lumped capacity in the external circuits.

The invention described above has general application to multivibrators and wave generators and, therefore, many changes may be made in the arrangements and modifications selected as examples for describing and illustrating the invention.

What is claimed is:

1. A wave generator comprising in combination an evacuated envelope, an electron gun mounted in one end of said envelope, said electron gun having a cathode and being adapted to project a continuous ribbon beam of electrons, a first target and a second target mounted so as to intercept said beam of electrons, a first deflection plate and a second deflection plate mounted on either side of the neutral position of said beam, said deflection plates being adapted to deflect said beam along a line that is perpendicular to the plane of said ribbon beam, a source of potential having positive and negative terminals, a first resistor connected between said first target and said positive terminal, said first deflection plate being coupled to said resistor, a second resistor coupled between said second target and said positive terminal, said second deflection plate being coupled to said second resistor, a third target mounted between said first and second targets so that the electron beam strikes it as it moves back and forth between the first and second targets, a load and a source of fixed potential connected in series between said third target and the cathode of said electron gun.

2. Wave generating apparatus comprising in combination an evacuated envelope, an electron gun having a cathode and adapted to project a

continuous flat beam of electrons, a first deflection plate, a second deflection plate, said plates being mounted on either side of said beam and so as to be parallel to the beam, a source of fixed potential having positive and negative terminals, said negative terminal being coupled to said cathode, a first target and a second target, said targets being mounted so as to be capable of intercepting said beam of electrons at its extreme point of deflection, a first resistor connected in series between the positive terminal of said source of fixed potential and said first target, a second resistor connected between said positive terminal and said second target, a third resistor connected between said cathode and a point on said first resistor, a fourth resistor connected between said cathode and a point on said third resistor, said first deflection plate being connected to a point on said third resistor and said second deflection plate being connected to a point on said fourth resistor, a third target mounted between said first and second targets, and a load impedance connected between said third target and said positive terminal.

3. Apparatus as described in claim 2 wherein

said deflection plates are adapted to focus the beam of electrons projected by said gun at said targets.
